Primary Examiner — Karen S Acker*(74) Attorney, Agent, or Firm* — Nixon & Vanderhye PC(57) **CLAIM**

The ornamental design for a mug with a lid, as shown and described.

DESCRIPTION

Fig. 1.1 is a perspective view of a mug with a lid according to my new design;

Fig. 1.2 is front view thereof;

Fig. 1.3 is a bottom plan view thereof;

Fig. 1.4 is a top plan view thereof;

Fig. 1.5 is a right side view thereof;

Fig. 1.6 is a left side view thereof.

The back view is not shown because it is symmetrical to the front view.

The broken lines depict portions of the mug with a lid that form no part of the claimed design.
